Website, product details of Audio-Technica headphone model ATH-F5CX in blue and orange, <http://www.audio-technica.co.jp/ati/products/hp/ath-f5cx.html>, Audio-Technica Corporation, obtained Feb. 26, 2019, model made available for sale Apr. 21, 1997.

Primary Examiner — Paula Allen Greene

(74) *Attorney, Agent, or Firm* — Michael Best and Friedrich LLP

(57) **CLAIM**

The ornamental design for a headphone, as shown and described.

DESCRIPTION

FIG. 1 is a perspective view of a headphone showing my new design;

FIG. 2 is a front elevational view thereof;

FIG. 3 is a rear elevational view thereof;

FIG. 4 is a right side elevational view thereof; and,

FIG. 5 is a bottom plan view thereof.

The broken lines illustrating unclaimed portions of the headphone form no part of the claimed design. The dot-dash broken lines defining boundaries of the claimed design form no part of the claimed design; all broken lines are for illustrative purposes only and form no part of the claimed design.

1 Claim, 5 Drawing Sheets
